UNITED STATES PATENT OFFICE.

MATTHEW JOSEPH SCHACKMANN, OF CHICAGO, ILLINOIS.

IRONING BOARD.

Application filed May 26, 1923. Serial No. 641,654.

To all whom it may concern:

Be it known that I, MATTHEW JOSEPH SCHACKMANN, a citizen of the United States, residing at Chicago, in the county of Cook 5 and State of Illinois, have invented certain new and useful Improvements in Ironing Boards, of which the following is a specification, reference being had to the accompanying drawings.

10 This invention relates to certain improvements in ironing boards and it is an object of the invention to provide a novel and improved device of this general character which may be readily supported in working position from a table or the like and in a manner obviating the necessity of using supporting legs or kindred structure.

Another object of the invention is to provide a novel and improved ironing board 20 provided at one end portion with means whereby the same may be effectively clamped to a table or the like and in a manner whereby the board is maintained in proper position for use.

25 The invention consists in the details of construction and in the combination and arrangement of the several parts of my improved ironing board whereby certain important advantages are attained and the device rendered simpler, less expensive and otherwise more convenient and advantageous for use, as will be hereinafter more fully set forth.

The novel features of my invention will 35 hereinafter be definitely claimed.

In order that my invention may be the better understood, I will now proceed to describe the same with reference to the accompanying drawings, wherein:—

40 Figure 1 is a view in perspective illustrating an ironing board constructed in accordance with an embodiment of my invention;

Figure 2 is a view in side elevation with a portion broken away of my improved ironing board as herein disclosed, a coacting support being shown in fragment;

Figure 3 is a fragmentary view in bottom plan of the ironing board as herein disclosed particularly illustrating the clamping means 50 associated therewith;

Figure 4 is an enlarged fragmentary sectional view taken substantially on the line 4—4 of Figure 2;

Figure 5 is an enlarged sectional view 55 taken substantially on the line 5—5 of Figure 2.

As disclosed in the accompanying drawing, B denotes an ironing board of desired dimensions and configuration and which has secured to one end portion adjacent a side 60 margin thereof a block 1. Underlying the block 1 is a side portion of a plate 2 said plate being of a width to extend inwardly of the block 1 and having its inner marginal portion beveled as at a. The inner end portion of the board B is adapted to be superimposed upon a table T or other support and the plate 2 underlying the marginal portion of such support, the bevel a facilitating such application.

The under surface of the board B at a predetermined point inwardly of the plate 2 but in relatively close proximity thereto is provided with a depending member 3 held to the board B in any desired manner but herein disclosed as through the instrumentality of the coacting bolts 4 and nuts 5. As illustrated in the accompanying drawings the member 3 comprises separable parts to facilitate the proper mounting or application of the clamping plate C.

The member 3 is provided with an elongated opening 6. The upper and lower walls of which being oppositely chamfered.

The clamping plate C hereinbefore referred to is provided at diametrically opposed points with the recesses 7 providing a neck 8 which fits substantially snug within the opening 6, the chamfered walls of the opening 6 permitting said plate to have 90 swinging movement toward or from the board B. The outer end portion of the plate C is provided with a slot 9 in which is engaged a cam 10 rotatably supported by the pin 11 carried by the plate C. The cam 10 95 has extending therefrom an operating member or handle 12.

When the board B is engaged with the table or other support T as hereinbefore described, the inner portion of the plate C is 100 disposed below a second marginal portion of the table or support T, it being understood that when the board is being initially engaged with the table or support T the cam 10 is adjusted with its low point adjacent to the board B, as is illustrated in Figure 1.

After the board has been properly mounted upon the table or support T the cam is swung to bring the high point thereof in contact with the board B, such operation of the cam 10 which is effected through the medium of the operating member or handle

12, causes the portion of the plate C underlying the table or support T to firmly clamp thereagainst whereby the board B is effectively maintained in a working position and 5 properly supported by the table or support T without the necessity of employing legs or kindred supporting means to afford additional support for the board B.

From the foregoing description it is 10 thought to be obvious that an ironing board constructed in accordance with my invention is particularly well adapted for use by reason of the convenience and facility with which it may be assembled and operated, 15 and it will also be obvious that my invention is susceptible of some change and modification without departing from the principles and spirit thereof and for this reason I do not wish to be understood as limiting 20 myself to the precise arrangement and formation of the several parts herein shown in carrying out my invention in practice except as hereinafter claimed.

I claim:—

25 1. In combination, an ironing board, a plate arranged at one extremity of the board and underlying a side marginal portion thereof, said plate being spaced from the board, means for securing the outer side 30 marginal portions of said plate to the adjacent side marginal portion of the board, said plate being adapted to underlie a marginal portion of a support, and clamping means carried by the board in advance of

the plate and adapted to engage a second 35 marginal portion of the support.

2. In combination, an ironing board, a plate arranged at one extremity of the board and underlying a side marginal portion thereof, said plate being spaced from 40 the board, means for securing the outer side marginal portions of said plate to the adjacent side marginal portion of the board, said plate being adapted to underlie a marginal portion of a support, a member 45 depending from the board inwardly of but spaced from the plate, said member being provided with an elongated opening, the upper and lower walls of which being each oppositely chamfered, a clamping plate, 50 said plate intermediate its ends being provided with recesses in its side marginal portions to provide a neck fitting substantially snug within the opening of the depending member, the chamfered walls of the opening of said member permitting the plate to have swinging movement toward or from the board, and means carried by the outer end portion of the plate and coacting with 55 the board for forcing the inner end portion of the plate toward the board, said last named end portion being adapted to be disposed below a marginal portion of said support.

In testimony whereof I hereunto affix my 60 signature.

MATTHEW JOSEPH SCHACKMANN.
